United States Patent Office.

SAMUEL D. HOVEY, OF BROOKLYN, NEW YORK.

Letters Patent No. 80,485, dated July 28, 1868.

IMPROVEMENT IN RUBBER HEADS FOR PENCILS.

The Schedule referred to in these Letters Patent and making part of the same.

TO ALL WHOM IT MAY CONCERN:

Be it known that I, SAMUEL D. HOVEY, of Brooklyn, in the county of Kings, and State of New York, have invented certain new and useful Improvements in Rubber Heads for Pencils; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in making a head or cap for pencils and pens of a combination of materials, so that one part shall be adapted to erasing pencil-marks, and the other part to the erasure of ink-marks, as hereinafter more fully explained.

Figure 1 is a perspective view of a pencil, with my improved head applied.

Figures 2, 3, and 4 are longitudinal sections of heads variously modified.

In the manufacture of this class of articles it has been customary hitherto to make them of the ordinary rubber used for erasing pencil-marks, and these were adapted to no other purpose or use. It is to remedy these defects, and produce a better article, one that is adapted to a greater range of operations, that my invention is intended.

To construct my improved head, I provide a mould, having a cavity of the form of the head, as represented in fig. 1, in which the neck *a* is made tubular, to fit on the end of a pencil, as usual with this class of articles. The two kinds are used in forming the head *B*. They are so arranged as to form one portion of the head of one kind, and another portion of the other kind, thus combining in the one head both the ordinary pencil-eraser, and also the ink-eraser, *o* representing the former and *e* the latter in the various figures. The ink-eraser portion may be arranged to occupy one side, as shown by *e* in fig. 2, in which case it will be seen that the head presents an ink-eraser on one face, and a pencil-eraser on the opposite face, while the two remaining sides and the end will present a surface having the two combined. Thus I am enabled to produce a pencil-head possessing advantages never before presented to the public, and which can be sold at the same rates as the ordinary article.

Having thus described my invention, what I claim, is—

The pencil and pen-head or tip, composed of the pencil-mark eraser *o* and the pen-mark eraser *e* combined, substantially as described.

SAMUEL D. HOVEY.
